ABSTRACT OF THE DISCLOSURE

Means are provided for using a single electroplating barrel with either disc type or dangler type plating cathode conductors. A bearing ring assembly that is permanently secured to each transverse end wall of the electroplating barrel is used with both types of cathodes. When using the dangler type cathode conductor, nylon bearing means and a Teflon washer and bearing ring are inserted into each bearing ring assembly and a dangler is then passed through each bearing ring from a position external of the barrel to terminate inwardly of the barrel in the usual manner. When using the disc type cathode conductors, suitable rubber sealing rings and Teflon bushings are used in conjunction with a metallic bearing stud shaft that extends outwardly of the drum and which terminates in the conventional hanger bearing assembly.

This invention relates generally to electroplating apparatus and more particularly to a kit for converting the rotary barrel of electroplating apparatus from the dangler type cathode conductor to the disc type cathode conductor and vice versa.

In electroplating, by the use of mechanism of the barrel type, it is customary to employ a rotating cylinder that is immersed within an electrolyte. Materials that are to be plated are deposited within the confines of the barrel. In the past, two different types of barrels have been employed. The first is called the dangler type because the cathode conductors extend through the end walls of the barrel and their free ends are loosely positioned within the interior of the barrel. The second or disc type has cathode conductors that are secured to the interior surface of the transverse end walls of the barrel. For both types of apparatus anodes are positioned on the exterior of the barrels and within the tanks that contain the electrolyte.

It is conventional in the electroplating art to provide means for raising and lowering the barrel out of and into the solution contained within the tank. It is also conventional to provide drive means external of the tank, the drive means cooperating with gears mounted on the outer surface of the barrel for angularly driving the barrels when it is immersed in the electrolyte. It is well known, particularly in the plating art, that the disc type cathode conductors have certain advantages when particular types of workpieces such as relatively large components are to be plated. Similarly, the dangler type cathode conductor has its own advantages, for example, when flat components that tend to stick together are to be plated. The particular type of cathode conductor selected depends upon the size and shape of the workpiece to be plated.

It has been customary in the past for electroplaters to purchase a barrel or cylinder with either the disc type or the dangler type cathode conductor for specific types of work. However, as frequently happens, the electroplater must convert from one type of work to another and this has usually entailed the use of a different type of barrel with a different conductor. It will be readily apparent that the cost for maintaining two separate plating

2

installations is excessively costly. Quite apart from the unnecessary duplication of equipment is the fact that when one type of plating apparatus is being used, the other will frequently be unused.

5 A typical example of the prior art is described in U.S. Pat. No. 2,315,272 issued to K. T. Potthoff on Mar. 30, 1943. While the patentee states that the barrel is the same for both the dangler and the disc types of cathode conductor, he nevertheless fabricates the barrel from separate 10 end plates that are secured to the cylindrical portion by means of bolts. With this type of construction it is then possible for the patentee to alter the inside surface of the end plates to accommodate the dangler type cathode conductor. It is apparent that what the patentee intends is 15 to use different end plates for each type of cathode conductor and thus, in effect, require two different barrels.

By way of contrast, the present invention utilizes only a single barrel the end plates and cylindrical portion of which are molded as an integral unit. No bolts are required, nor are seals for eliminating leakage. Each end plate in the present invention has a single central bore that accommodates either one of two different sets of components. The first set of components permits a disc type of cathode conductor to be removably attached to the inside surface of the end walls. The second set of components permits the use of a dangler type cathode conductor that extends through the end walls of the same barrel that was used with the disc type cathode conductor. Thus, the basic concept of the present invention is in direct 30 contrast to the prior art.

Accordingly, it is a primary object of the present invention to provide improved electroplating apparatus.

Another object of the present invention is to provide 35 a kit whereby a single electroplating barrel may be used with two different types of cathode conductors.

An important feature of the present invention is that a single electroplating barrel may be converted so as to be usable with either one of two different types of cathode conductors without the need for special tools or skills.

40 Other and further objects and advantages of this invention will become apparent in the following description when considered in connection with the accompanying drawings in which:

45 FIG. 1 is a perspective view of the conversion kit comprising the present invention wherein a dangler type of cathode conductor is employed;

FIG. 2 is another perspective view of the conversion kit comprising the present invention illustrating the use 50 of a disc type cathode conductor;

FIG. 3 is an enlarged, fragmentary side elevational view, partially in section, illustrating a portion of a typical end wall of the apparatus shown in FIG. 1 together with a dangler type cathode conductor; and

55 FIG. 4 is an enlarged, fragmentary side elevational view, partially in section, illustrating the disc type cathode conductor shown in FIG. 2.

Referring now to the drawing and in particular to FIG. 60 1, there is shown an electroplating system that includes a perforated, polypropylene plating barrel 10. There is also provided a tank 12 for an electrolyte and a motor 14 mounted on an extension 16 of the tank 12. Speed reducer means 18, mounted on the extension 16 and driven by the motor 14, includes an output pinion (not shown) that is adapted to meshingly engage with a drive gear 20 when the barrel 10 is lowered into the tank 12. Another gear 22 coaxially mounted on the same shaft as gear 20 is permanently in meshing engagement with 65 a ring gear 24 that is mounted on an end wall of the barrel 10. The aforementioned structure provides for rotation of the barrel 10.

Means not shown are provided for raising and lowering the barrel 10 into and out of the tank 12 so that the gear 20 meshingly engages with the gear of the speed reducer means 18. Further, bus bar means 26 are provided externally of the barrel in order to mate with contact means 28 positioned on top of tank 12, when the barrel 10 is lowered into the tank 12. In FIG. 2 the bus bar means are designated by the reference character 26'. All of the foregoing is conventional in the electroplating art.

Referring now particularly to the barrel 10 it will be seen that it is substantially cylindrical in transverse cross section but it should be clearly understood that the invention is not so limited. The barrel 10 may also be octagonal or polygonal. The barrel 10 includes a perforated, circumferential wall 30 and a plurality of longitudinally extending, thickened ribs 32 for structural purposes. One portion of the wall 30 is removable so as to define an access door 34 that is secured to the barrel 10 by means of conventional spring clips 36. End walls 38 of the barrel 10 are solid and are molded integrally with the polypropylene barrel 10. A conventional dangler type cathode 40 extends through a central opening 39 formed in each of the end walls 38.

Since both end walls 38 are substantially the same only one need be described. Reference may now be had to FIG. 3 for a detailed discussion of one aspect of the conversion means comprising the present invention. A bearing ring assembly 42, having a central bore 44, is secured to the end wall 38 by means of a plurality of screws 46 and preferably by means of a weld as well to make the connection permanent. A nylon bearing ring 48 is inserted with a press fit into the bore 44 of the bearing assembly 42. The bearing ring assembly 42, including the bearing ring 48 while actually used with only the dangler type of cathode conductors may be left in place when the disc type anode conductor is used.

For use with the dangler type cathode conductor 40, a Teflon thrust washer 50 is inserted within the bearing ring 48 in abutment with the outside surface of the end wall 38, and a Teflon retaining ring 52 is seated on the thrust washer 50 within the inside diameter of the bearing ring 48. While the washer 50 and the ring 52 have been shown as separate components it should be evident that they could be fabricated as a single unit. A nylon bearing 54, having a central bore 56 and a cylindrical extension 58 depending coaxially from one end thereof is formed integrally as a unitary member. As shown in FIG. 3, the extension 58 fits into the central opening 39 formed in the end wall 38. Screws 60 are used to secure the bearing 54 to a conventional rubber coated hanger means 62 prior to the final assembly shown in FIG. 3. It will be noted, particularly in FIG. 3, that the dangler type cathode conductor 40 extends through the hanger means 62, through the central bore 56 formed in the bearing 54 and thus through the wall 38 into the interior of the tank 10.

From the foregoing it will be readily appreciated that the portion of the conversion kit that is adaptable for use with the dangler type cathode conductor may be readily assembled and disassembled with a minimum of special skills and without the need for specialized tools.

As mentioned above the bearing ring assembly 42 and the bearing ring 48 are used with both types of cathode conductors. Thus in FIG. 4 it will be seen that these two components are still in place while the thrust washer 50, the retaining ring 52 and the bearing 54 have been removed. In their place there is shown in FIG. 4 the components that are used with the brass or steel disc type cathode conductor 70.

A stud bushing 72 made of hard rubber is positioned in the opening 39 formed in the end wall 38 and a sealing bushing 74, also made of hard rubber, is positioned about the stud bushing 72 externally of the outer surface of the wall 38. While the bushings 72 and 74 have been

illustrated as separate components, it is evident that they may be fabricated as a single element. A soft rubber sealing ring 76, a hard rubber sealing washer 78 and a Teflon seal washer 80 are positioned about the stud bushing 72 and the seal bushing 74. A steel bearing stud 82 is secured to the inside surface of the wall 38 by means of screws 84. One end 86 of the bearing stud 82 extends through the wall 38 and the stud bushing 72 into the lower end of conventional, rubber covered hanger means 88 in which lubricating grooves are formed in a well known manner. The other end 90 of the bearing stud 82 is threaded and passes through a polypropylene thrust plate 92 before it is captured by a canvas base melamine lock nut 94.

An analysis of FIG. 4 will reveal that the components comprising the conversion kit for use with a plate or disc type cathode conductor may be readily assembled and disassembled when changing from one type of electroplating to another.

From the foregoing it will be evident that improved electroplating apparatus has been provided wherein a single, polypropylene barrel may be used with either dangler or disc type cathode conductors. No alterations need be made to the barrel when converting from one type of cathode conductor to the other. That is, the end walls of the barrel are not changed or in any way altered other than to substitute one set of bushings, rings and washers for another set. This may be done very rapidly and simply with tools having a complexity of the order of a screw driver or wrench. Thus the rather substantial expense of maintaining two completely separate plating systems is avoided. Further, special skills are not needed to rapidly affect the changeover.

Various changes within the scope of the invention described hereinabove and illustrated in the drawing may suggest themselves to those skilled in the art. Accordingly, the invention is not to be limited to the specific embodiment shown and described which are intended to exemplify the scope of this invention which is limited only in the appended claims.

What is claimed is:

1. For use with electroplating apparatus of the type having a pair of spaced conductive hanger bearing assemblies, the combination of:

(a) an insulating barrel having a perforated, cylindrical body portion, a door in said body portion for permitting access to the interior thereof and a pair of axially spaced, transverse end walls integral and non-removable with respect to said body portion, each said end wall having a bore therethrough;

(b) means for rotating said barrel about the longitudinal axis thereof; and

(c) a cathode conductor kit comprising:

(1) an annular bearing ring assembly secured to the outside surface of each said end wall concentrically with the bore therethrough;

(2) a pair of dangler type cathode conductors;

(3) first bearing means adapted to be mounted on each said end wall within said annular bearing ring assembly for supporting said pair of dangler type cathode conductors, said first bearing means having a central bore that is coaxial with the bore on each said end wall whereby said dangler type cathode conductors extend through said first bearing means with one end of each dangler type cathode conductor terminating in the interior of said barrel;

(3') a first pair of hanger bearing assemblies positioned outside said barrel proximate the end walls thereof for supporting said dangler type cathode conductors;

(4) fastener means for removably securing said first bearing means to said first hanger bearing assemblies;

(5) a pair of disc type cathode conductors;

- (5') a second pair of hanger bearing assemblies adapted to be positioned outside of said barrel proximate the end walls thereof for supporting said disc type cathode conductors;
- (6) elongated second bearing means adapted to extend through the central bore in each said end wall for supporting said disc type cathode conductors on the inner end thereof, the outer ends of said second bearing means terminating in said second hanger bearing assemblies; and
- (7) fastener means for removably securing said second bearing means to the interior surface of said end walls,
- (8) said annular bearing ring assemblies being maintained in place when either type of cathode conductors is used.

2. The combination in accordance with claim 1 wherein said first bearing means comprises:

- (a) a cup-shaped, plastic washer having a low coefficient of friction, the base wall of said cup-shaped washer having a bore therein positioned coaxially with the bore in said end wall, the base wall of said cup-shaped washer being in abutment with the outer surface of said end wall, the side wall of said cup-shaped washer being positioned within said annular bearing ring assembly; and
- (b) a hollow plastic bearing having a first diameter positioned internally of the side wall of said cup-shaped washer, a second coaxial diameter extending into the bore in said end wall and a transverse interface between said first and said second diameters, said interface bearing against the base wall of said cup-shaped washer.

3. The combination in accordance with claim 1 wherein said second bearing means comprises:

- (a) a hard elastomer bushing extending through the bore in said end wall and outwardly of said barrel and having an enlarged diameter abutting the outer surface of said wall;
- (b) a metallic bearing stud having a first end removably secured to the hanger bearing assembly, a second

- threaded end positioned internally of said barrel and a transverse flange intermediate said first end and said second end, said transverse flange abutting the inner surface of said end wall, said bearing stud being positioned within said stud bushing, said disc type cathode conductor being mounted on said second end of said bearing stud overlaying said flange;
- (c) a plastic thrust plate mounted on said second end of said bearing stud and overlaying said disc type cathode conductor;
- (d) an insulating lock nut threaded in said second end of said bearing stud for capturing said thrust plate and said disc type cathode conductor;
- (e) a soft elastomer seal ring positioned about a portion on the enlarged diameter of said seal bushing remote from said end wall; and
- (f) a hard elastomer seal washer and a plastic seal washer positioned in tandem about said stud bushing, said elastomer washer abutting the remote end of the enlarged diameter of said seal bushing, said plastic seal washer being positioned intermediate said elastomer washer and the hanger bearing assembly.
